US0D1040803S

(12) **United States Design Patent** (10) **Patent No.:** **US D1,040,803 S**
(45) **Date of Patent:** **** Sep. 3, 2024**

(54) **NOTEBOOK COMPUTER**

(71) Applicant: **Acer Incorporated**, New Taipei (TW)

(72) Inventors: **Szu-Wei Yang**, New Taipei (TW);
Yun-Ju Chou, New Taipei (TW);
Pao-Ching Huang, New Taipei (TW)

(73) Assignee: **Acer Incorporated**, New Taipei (TW)

(**) Term: **15 Years**

(21) Appl. No.: **29/850,531**

(22) Filed: **Aug. 22, 2022**

(30) **Foreign Application Priority Data**

Apr. 21, 2022 (TW) 111301920

(51) **LOC (14) Cl.** **14-02**

(52) **U.S. Cl.**
USPC **D14/315**

(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion, labeled '9' in FIG. 2;

FIG. 10 is an enlarged view of the portion, labeled '10' in FIG. 2;

FIG. 11 is a perspective view showing the notebook computer in an alternate configuration; and,

FIG. 12 is another perspective view showing the notebook computer in an alternate configuration.

The dashed broken lines illustrate portions of the notebook computer that form no part of the claimed design. The dot-dash broken lines illustrate the boundaries of the enlarged portions and form no part of the claimed design.

1 Claim, 10 Drawing Sheets
